UNITED STATES PATENT OFFICE.

SAMUEL M. DICK, OF MINNEAPOLIS, MINNESOTA.

AUTOMATIC AIR-BRAKE-HOSE COUPLING.

1,295,282.

Specification of Letters Patent. Patented Feb. 25, 1919.

Application filed May 3, 1915. Serial No. 25,410.

To all whom it may concern:

Be it known that I, SAMUEL M. DICK, a citizen of the United States, residing at Minneapolis, in the county of Hennepin 5 and State of Minnesota, have invented certain new and useful Improvements in Automatic Air-Brake-Hose Couplings; and I do hereby declare the following to be a full, clear, and exact description of the invention, such as will enable others skilled in the art to which it appertains to make and use the same.

My invention has for its object to provide an extremely simple and highly efficient 15 automatic hose coupling mechanism for railway trains, and to such ends, generally stated, the invention consists of the novel devices and combinations of devices hereinafter described and defined in the 20 claims.

The invention is illustrated in the accompanying drawings wherein like characters indicate like parts throughout the several views. Referring to the drawings:

25 Figure 1 is a view in side elevation with some parts broken away and some parts removed showing my improved hose coupling mechanism applied to and supported from car couplers of the Master Car Builders' type:

30 Fig. 2 is a fragmentary detail in section taken through one of the hose coupling heads on the line $x^2 x^2$ on Fig. 3;

35 Fig. 3 is a horizontal section taken on the line $x^3 x^3$ on Fig. 1, showing the hose coupling heads separated;

Fig. 4 is a rear elevation of the connected hose coupling heads shown in Fig. 1;

40 Fig. 5 is a vertical section taken on the line $x^5 x^5$ on Fig. 4; and

Fig. 6 is a view looking downward at the coupling heads shown in Fig. 4 at an angle of 45 degrees, and showing the said hose coupling heads slightly separated.

45 The numeral 1 indicates car couplers which, as stated, are shown as of the standard Master Car Builders' type. The drawbars of these couplers are connected in the usual way to the car bottom, portions of 50 which are indicated by the numeral 2. The numeral 3 indicates portions of the customary draft rigging through which the couplers are connected to the car sills. The numeral 4 indicates drawbar supporting 55 yokes connected to the ends of the car frames in the usual way and through which

the drawbars of the couplers work with freedom for endwise and limited lateral swinging movements. The hose couplers are located under and are supported directly from the car coupler heads or their drawbars, and hence, are arranged to swing laterally therewith, by means of supporting brackets 5 rigidly secured to and depending from the said drawbars. Each of 60 these hose couplers comprises a rectangular head 6 set with its face in a vertical plane, but with its marginal edge set 45 degrees to a vertical. Each head 6 is provided at one side with a flaring angular 70 or L-shaped alining flange 7. The head and flange of the one coupler head are counterparts of the head and flange of the other, and hence, do not need to be made in rights and lefts, but are brought into 75 proper coöperative relation simply by turning the two hose coupling heads face to face. When the two coupler heads are face to face, the flange of one projects one side and the flange of the other at the other 80 side of the axis of the hose coupler. For example, as shown in the drawings, the alining flange of the hose coupling head projects on the left hand side thereof, directions being taken in respect to a person 85 standing at the rear of the said coupler head, and hence forward.

Freight trains usually have but one air pipe with flexible hose couplings, whereas, 90 passenger trains usually have three such pipes, to-wit, one for the air brakes, one for the air signaling system, and the other for the steam heating system. The drawings show the hose coupling heads provided with connections for the three pipe systems, and for such purpose, each coupling head is provided with three tubular stems 8 located vertically, one over the other and horizontally extended rearward from the coöperating coupler head. At their rear 100 ends, the said stems are adapted to be connected to the respective flexible hose sections not shown, by coupling devices of any suitable or well known construction. The centrally located stem 8 is passed loosely 105 through a bearing sleeve 5^a of the coöperating hanger 5, and the said hanger bracket is provided higher up with a perforation 5^b through which the upper stem 8 is passed with freedom for sufficient lateral and vertical oscillation, to permit the required 110 alining movements of the hose coupling

heads, when on curved, as well as when on straight tracks. Coiled springs 9 are placed around the central stems 8 and are compressed between the bearing sleeves 5^a and the rear faces of the hose coupling head 6. These springs tend to hold the hose coupling heads in intermediate positions, and when two hose coupling heads are forced together, the said springs 9 will 10 be compressed and will serve to hold the faces of the said heads tightly pressed together. When the hose coupling heads are separated the springs 9 will throw the same forward as far as permitted by stop 15 nuts 10 and pliable cushioning washers 11 applied on the central stem 8.

At their outer extremities, that is at the outer faces of the hose coupling heads 6, the several tubular stems 8 open against 20 and are alined with axial perforations of annular diaphragms 12, preferably of rubber. These diaphragms 12, immediately surrounding their axial perforations, are of such thickness that they project slightly beyond the outer faces of the respective heads 6, but they are provided with reduced marginal flanges that are held by annular clamping rings 13, which, in turn, are held in place by externally threaded clamping 30 rings 14 that have screw threaded engagement with seats countersunk into the said heads. The said rings 13 and 14 tightly clamp the reduced marginal portions to the diaphragms 12 against annular bosses 35 15 formed on the faces of the head 6; and the said heads immediately inward of said bosses 15 are provided with annular chambers 16 that surround the inner extremities of the passages that lead from the stems 40 8. These annular chambers 16 communicate with the axial passages, through radial ports 17.

When the hose coupling heads are forced together by coupling of the car couplers 1, 45 as shown in Figs. 1 and 5, the thick portions of the diaphragms 12 will be tightly pressed together by the very act of coupling; and when the air or steam is turned on, the pressure thereof, acting in the annular chamber 50 16, against the inner faces of the diaphragms, will increase the pressure between the said diaphragms, to the same pressure found upon the walls of the stems 8, and thereby insure tight joints required to prevent leakage. The springs 9 must, of course, be of 55 sufficient tension to hold the diaphragms in engagement under the pressure required to maintain the said tight joints.

Obviously, as the several tubular stems 8 60 are vertically arranged, one over the other, they will always be brought together in the same relative arrangement. For example, if the central tubes 8 be used for the air brake system, the lower tubes for the steam system and the upper tubes for the signal-

ing system, then corresponding tubes on different cars will always be properly coupled together.

With the above described arrangement of the alining flanges of the hose coupling heads, the alining movement is always in one direction, and hence, said hose coupling heads are preferably offset laterally from the axes of the drawbars so that they will usually, or in average conditions, come into 75 initial contact when approximately in the relative positions shown in Fig. 3. For example, if we assume that the alining plates have a bevel or gather of six inches then the said hose coupling heads will be set so that 80 under ordinary conditions, they will come into initial contact when laterally offset from each other about three inches. This allows for proper alinement of the hose coupling heads when offset from each other 85 under extreme conditions ranging from initial alinement to a maximum of six inches offset.

The said alining flanges will, in themselves, bring the hose coupling heads into 90 approximate alinement, but to effect the final and more accurate alinement of the several ports or conduits, I provide each coupler head with a forwardly projecting conically pointed dowel pin 18 that is adapted to register with a perforation or seat 19 in the co-operating hose coupling head. Both the alining flanges 7 and the dowel pins 18 serve to aline the ports of the hose coupling heads, both by important lateral motion 100 thereto, and by imparting a slight rotation thereto, one in respect to the other, required for true alinement of the said ports. The dowel pins also form a secure lock of coupler heads when in action, preventing any slipping when cars are in motion.

By providing the hose coupling heads with alining flanges on one side only, not only is the construction very greatly simplified, and made strong, but there is no possibility of the alining flanges of the two hose coupling heads being brought into engagement with each other or into any obstructive conflict whatever. Furthermore, the said alining plates may be given a large range of 115 gathering action. The square or approximately rectangular form of the coupler heads and the corresponding angular form given to the alining flanges greatly facilitates the alining action of the two hose coupler heads 120 noted, in respect to lateral movement and in respect to angular or rotary motion. Furthermore, the hose coupling heads are given flat opposing faces of very considerable area which is advantageous for alining purposes, 125 and for keeping the hose coupling heads in alinement when pressed together.

What I claim is:

1. The combination with a coupler head provided with an air port and having an off- 130

set alining surface that is rectangular in cross section and flares up from the axis thereof, the said coupler head also having a conical dowel pin adapted to engage a seat in a corresponding head and having also an angular portion for engagement with the rectangular flange of a coöperating coupler head.

2. The combination with a car coupler, of
10 an automatic hose coupling head yieldingly supported therefrom, said hose coupling head having an axial port and provided with oblique alining surfaces in angular relation in respect to each other, projecting
15 forward therefrom entirely at one side of the axis of said port, the said hose coupling head being normally supported with its axis offset laterally from the axis of said car coupler, in a direction opposite to the oblique projection of its said alining surfaces, and the said head having a forwardly projecting dowel pin adapted to register with a seat in a companion head, and having a
20 dowel pin seat adapted to be engaged by a
25 dowel pin of a companion hose coupling head.

3. The combination with a car coupler, of an automatic hose coupler yieldingly supported therefrom, said hose coupler having a rectangular head with flat face and vertically spaced ports, and provided on one side of the vertical plane of the axes of said ports with a forwardly projecting oblique alining flange that is angular in cross section. 30

4. The combination with a car coupler, of an automatic hose coupler yieldingly supported therefrom, said hose coupler having a rectangular head with flat face and vertically spaced ports, and provided on one side of the vertical plane of the axes of said ports with a forwardly projecting oblique alining flange that is angular in cross section, and having further, at one side, a forwardly projecting tapered dowel pin and at the other side a corresponding dowel pin seat. 35 40 45

In testimony whereof I affix my signature in presence of two witnesses.

SAMUEL M. DICK.
